G. W. GRISWOLD.

Making White Lead.

No. 11,326.

Patented July 18, 1854.

UNITED STATES PATENT OFFICE.

GEORGE W. GRISWOLD, OF CARBONDALE, PENNSYLVANIA.

PROCESS OF SEPARATING IMPALPABLE POWDER FOR PAINTS.

Specification of Letters Patent No. 11,326, dated July 18, 1854.

To all whom it may concern:

Be it known that I, GEORGE W. GRISWOLD, of Carbondale, in the county of Luzerne and State of Pennsylvania, have invented or dis-
5 covered a new and useful Process for Prepar-
ing and Separating Impalpable Powder for
Paint, &c., and that the following is a full,
clear, and exact description of the same, ref-
erence being had to the accompanying draw-
10 ings, which illustrate one of the plans of
carrying out said process, and in which—

Figure 1 represents a side view of the
apparatus and Fig. 2 a vertical, longitudinal
section through the same.

15 Similar letters in both the figures denote
like parts.

In making paint from mineral coal great
difficulty is found in separating the impalp-
able powder, from the specula, and coarser
20 material, and unless this is done effectually,
the paint will have a grayish, instead of a
black appearance.

The nature of my invention relates to a
method of separating and depositing the
25 impalpable from the palpable powder, and
thus producing a durable and cheap black
paint, the material being ground and re-
ground until all is used.

To enable others skilled in the art to make
30 and use my invention or process, I will pro-
ceed to describe, in connection with the
drawings, an apparatus which has proved
entirely successful.

A chamber is first inclosed in a tight
35 metallic case A, and within this chamber is
hung upon a shaft B, a square box or recep-
tacle C, slightly inclined from front to rear
as shown in the drawing. I have used this
receptacle square because in revolving it
40 more effectually carries up and drops the
material to be separated; a round one with
radial flanges will answer equally well.
Above this chamber A, and communicating
with it by the passages D D', are the receiv-
45 ing chambers E, E', provided with doors
F F'. The front end of the lower chamber
is separated from the main chamber by a
partition G.

The coal from which the paint is to be
50 made may be first roasted, or it may be used
in its natural state. It is ground in a mill
as fine as possible, and introduced into the
apparatus through the spout or hopper H,
which leads it through what I term the air
55 chamber (I) into the rotating box C.

Heated or dry atmospheric air is intro-
duced into the apparatus through a pipe or
tube J, and I have found in practice that
air heated to about 110° Fahr. is the best for
the purpose. In mid-summer with a per-
60 fectly dry atmosphere the process may be
carried on without heat, but when humid,
the heated air must be used. And I also
find that, at times the heated air becomes
sluggish and does not carry up the powder 65
with regularity, either from reacting cur-
rents or a partial vacuum in the chamber A.
To remedy this, I use a fan K, which may
be rotated by a belt in any well known man-
ner, and when this fan is necessary or to be 70
used, a door L, opposite to it, is to be
opened, to admit the blast, which must be
very gentle into, and through the chamber
I, to the chamber A, and thence through the
passage D, and first receiving or depositing 75
chamber E, and then through the passage
D', and second receiving and depositing
chamber E', and thence passes out through
the screen or cloth covered opening M on
80 top. I have only represented two cham-
bers for receiving the impalpable powder
thus carried up, but any convenient number
may be used.

In order that a regular current of heated
air may be used, a thermometer may be at-
85 tached to the air chamber I, and although
as stated a less temperature may at times be
used, yet about 110° of heat will produce
the proper current for carrying up, and al-
lowing the material to settle or deposit. I 90
have also by this means very successfully
separated, sand, emery and ground glass,
into various degrees of fineness, for making
what is termed "sand paper."

Having thus fully described the nature of
my invention and shown how the same may
be reduced to practice, what I claim therein
as new and desire to secure by Letters Pat-
ent, is—

The process of separating and collecting 100
impalpable, from coarser substances, such
as ground coal for the purposes of paint,
or other mineral substances, by means sub-
stantially such, as herein described and rep-
resented.

G. W. GRISWOLD.
